Primary Examiner — Sheryl Lane*Assistant Examiner* — Benjamin D. Wannemacher(74) *Attorney, Agent, or Firm* — John Alumit**CLAIM**

I claim the ornamental design for a diamond saw blade, as shown and described.

DESCRIPTION

FIG. 1 is a top view of the diamond saw blade, as shown herein. The bottom view is a mirror image of the top view; and,

FIG. 2 is a cut-away perspective view of the diamond saw blade in FIG. 1.

The broken line reference bubble illustrates a graphical symbol provided to indicate the area of enlargement and do not form part of the claimed design.
